UNITED STATES PATENT OFFICE.

JAMES A. TODD, OF ATTALLA, ALABAMA, ASSIGNOR TO COMPRESS BUCKLE COMPANY,
OF FORT WORTH, TEXAS, A CORPORATION OF TEXAS.

BALE-TIE BUCKLE.

Application filed May 10, 1926. Serial No. 108,002.

My invention relates to bale tie buckles of the type usually employed for securing the ties or bands that are applied to bales of cotton, jute and other baled goods.

More particularly, my invention relates to bale tie buckles formed of bent wire to provide a closed end, side walls which are slightly divergent and are intended to bend into parallelism when in service, and free ends bent inwardly to form the open end of the buckle. In buckles of this type, it is customary to bend the free inturned ends so that they diverge on opposite sides from the plane of the buckle with the object that as the tension is applied to the loop of the band these free ends will be drawn inwardly towards position in the plane of the buckle. Also, it is desirable that the ends should be bent upwardly towards the closed end of the buckle so that when the whole strain comes on them they are free to bind down slightly and bring the divergent side walls into parallelism.

Heretofore, in general practice, the inbent ends have been of equal length so that their 25 joint comes substantially opposite the center of the band. I have conceived that the strength of buckles of this type can be materially increased if the joint can be brought so close to one side that the open end of the buckle will have practically the full strength 30 of the wire forming the buckle to resist the pull on the band, i. e., that the band will not be in such relation to the joint as to apply pressure on the buckle ends with any substantial leverage against the side walls of the 35 buckle that would tend to spread them and weaken or destroy the buckle. To attain this object, I design my present buckle with a short inturned end and a long inturned end so related that their lapped joint is 40 brought close to the side of the buckle carrying the short end.

My invention also contemplates that the long end, as it is drawn to operating position by the bite of the bale band, will so engage the short end that the latter will take the leverage strain from the long end and in effect constitute a support for the long end to withstand the strain thereon of the bale band that holds these parts in engagement.

I have conceived that the strength of the buckle will be further increased if means are provided to cause the inbent ends, as they are

drawn together by the strain on the band into operating position, to interlock, as such 55 an interlock will in a large measure prevent the possibility of the sides of the buckle spreading beyond parallelism. When such spreading occurs the strength of the holding ends is materially weakened and the buckle 60 is liable to give way. To this end I have designed the engaging portions of the long and short ends so as to provide interlocking 65 portions when such ends are deformed under tension strain from the band into their operating position. Preferably the side of the buckle carrying the short end is made longer than the side of the buckle carrying the long end and the latter end is disposed so as to be drawn both inwardly and downwardly as 70 the strain comes on the buckle until when the sides of the buckle assume parallelism this long end will stand at right angles to the sides and will be fully supported by and interlocked with the short end, making it 75 practically impossible under ordinary usage for the buckle sides to spread.

My invention will be better understood by reference to the accompanying specification and claims, and in its preferred embodiment 80 only will be found illustrated in the accompanying drawings which form a part of this specification, and in which:—

Fig. 1 is a plan view of the buckle, before the band is applied, the band being shown 85 in preliminary position in dotted lines.

Fig. 2 is an end of Fig. 1.

Fig. 3 shows the tie buckle in plan with the band under full tension in operating position with the buckle sides spread into parallelism and with the bale band broken away to show the buckle in full view.

Fig. 4 is a cross-sectional view taken on the line 4—4 of Fig. 3, and showing the overlapping operating position of the buckle ends. 95

Fig. 5 is a perspective view of the buckle.

Similar reference numerals refer to similar parts throughout the drawings.

In the embodiment of my invention illustrated, I show a bale tie buckle as formed 100 of bent wire having a closed end 1, a long side 2 and a short side 3, the short side being initially bent so that it will converge towards the longer side 2 which is preferably parallel with the long axis of the buckle. 105 The long side 2 terminates in a short inbent

end 4 and the side 3 terminates in a long in-bent end 5 which is preferably straight and in length will be but slightly less than the distance between the buckle sides when parallel. Both ends 4 and 5 may be caused to diverge oppositely from the plane of the buckle if desired, but it is only essential that the leg 5 shall diverge and that this divergence shall be sufficient to facilitate the insertion of the tie loop over the leg 5 so as to set it in the buckle. The leg 4 can be made as short as is practical with the type of wire and the bending operation necessary to provide not only the right angled bend but the indentation 6 with a former at its junction with the side 2 and on the side facing towards the closed end 1. This indentation leaves a hump or shoulder on the end 4 which will be engaged by the end 5 when the buckle is in service. In like manner, the free end of the buckle end 5 is deformed to provide a hump or shoulder 7 disposed and shaped to interlock with the hump, left by the indentation 6 on the buckle end 4, when in service, as will be more clearly seen in Fig. 3. The relative length of the legs 2 and 3 is preferably such that the end 5 when drawn into its operating position, as shown in Fig. 3, will be at right angles to the legs 2 and 3, which will at the time be parallel. Regardless of the length of the end 4 the strain on the end 5, which is free, will be sustained as close as possible to the leg 2.

In operation, the loop 8 of the band can be inserted between the ends 4 and 5 in the manner well understood in this art and will assume initially the position shown in dotted lines in Fig. 1. As tension is applied, the loop is drawn down between the sides 2 and 3 until it engages the ends 4 and 5 and as the tension on the band loop increases the end 5 is drawn towards the end 4 and both ends are drawn into the plane of the buckle so that under full service conditions the end 5 will rest on the end 4 with its shoulder 7 interlocked in the notch 6 of the end 4 and these ends will be held interlocked in this position by the loop of the band which will have spread the buckle side 3 outwardly until it assumes parallelism with the side 2. With the ends 4 and 5 thus held in interlocked relation by the band loop, it will be apparent that the strain on the band is taken up by the end 5 which is fully supported at one side by the side 3 of the buckle, of which it forms a part, and at the other side it is supported by engagement with the short arm 4 practically at its point of junction with the side 2 of the buckle, and thus the end 5 has practically the same strength as if it formed a part of both sides 2 and 3. The conformation of the interlocking portions of the ends 4 and 5 is preferably such that as these ends are drawn and deformed towards operating position they will

engage and cause the ends to force the sides 2 and 3 into parallelism as the ends interlock and thus they provide a positive means for drawing the buckle 2 into the correct working position.

It is within the contemplation of my invention that the interlock of the ends forming the open end of the buckle may be accomplished in a variety of ways responsive to the deformation of said ends by the loop of the band and I have only sought to illustrate the one way which I consider as preferred for accomplishing this end.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. A bale tie buckle formed of bent wire forming a closed end, sides and inturned free members adapted to be received in the bight of the bale tie and normally spaced to form the open end of the buckle, one of said members being substantially shorter than the other and adapted to sustain at its end adjacent to a buckle side the load strain on the longer tie engaging member when in service.

2. A bale tie buckle according to claim 1, in which the buckle side carrying the shorter inturned member is longer than the other buckle side.

3. A bale tie buckle according to claim 1, in which the side of the buckle carrying the shorter inturned member exceeds the other side in length to an extent approximately equal to the diameter of the wire forming the buckle.

4. A bale tie buckle of bent wire formed to provide a closed end, sides, and inturned ends on the sides adapted to be received in the bight of the bale tie and which co-act to form the open end of the buckle, one side of the buckle being longer than the other and the shorter side of the buckle having its inturned end substantially longer than the inturned end of the longer side of the buckle, the shorter inturned end being adapted to be engaged by the longer inturned end when in service and support it at a point adjacent to the bottom end of the longer buckle side.

5. A bale tie buckle according to claim 4, in which the longer side of the buckle is parallel with the long axis of the buckle and the shorter side at its free end converges towards the longer side.

6. A bale tie buckle, comprising a metallic frame having a closed end, sides and an open end formed by inturned portions of the sides, said portions being adapted to lie wholly

within the plane of the buckle and to engage and interlock with one member overlying the other as they are deformed by the tension of the bale band loop.

- 5 7. A bale tie buckle having an open end formed by diverging flexible portions adapted to be engaged within the loop of the bale band and drawn together by the tension on said loop, said portions having shoulders 10 which lie in the plane of the buckle and interlock when they are drawn together and hold the sides of the buckle against spreading.

8. A bale tie buckle according to claim 7, in

which the longer of said portions as originally disposed is divergent from the plane of the buckle and is bent towards the closed end of the buckle. ¹⁵

9. A bale tie buckle according to claim 7, in which one of said portions has approximately a length equal to the distance between the sides of the buckle when parallel and which is adapted to engage and be supported by the other portion when in operating position. ²⁰

In testimony whereof I affix my signature.

JAMES A. TODD.
